UNITED STATES PATENT OFFICE.

JOHN V. PILCHER, OF LOUISVILLE, KENTUCKY.

BUTTON.

1,051,849.

Specification of Letters Patent. Patented Jan. 28, 1913.

Application filed May 15, 1911. Serial No. 627,266.

To all whom it may concern:

Be it known that I, JOHN V. PILCHER, a citizen of the United States, residing at Louisville, in the county of Jefferson and 5 State of Kentucky, have invented certain new and useful Improvements in Buttons, of which the following is a specification.

This invention relates in general to that class of garment buttons which are adapted 10 to be attached to a garment or detached therefrom by the fingers of the operator without the aid of any implement, each button having means for holding itself attached when in service; and more particularly to improvements in the button which is the subject of my former Patent No. 775,457.

The object of the invention is to adapt the locking key to hold itself directly to the button head either in its locked or unlocked 20 condition, to adapt the key to be easily and safely grasped by a person's finger and nail at any two sides, and to render the appearance of the button more finished and ornamental.

25 To this end my invention consists in the construction and combination of parts forming a button, hereinafter more fully described, and particularly stated in the claims, reference being had to the accompanying 30 drawing in which—

Figure 1 is a top view of a button according to my invention. Fig. 2 is a vertical section of the same through the whole length of the key legs. Fig. 3 is a perspective view 35 of the key without its cap. Fig. 4 is a vertical section of the key and cap at right-angles to the section shown in Fig. 2. Fig. 5 shows the form of the key blank. Fig. 6 corresponds with Fig. 2, excepting a modification of the key hips.

40 Numeral 7 represents the top plate, 8 the bottom plate, and 9 a ring, which three fixed parts comprise the button head. A stud 10, having a neck 11, a broader shoulder 12, and a point 13 to penetrate the fabric of the garment 23, is pushed through the same and up through the ring 9, and a broad base 14, prevents the stud from being pulled through. A key 15, punched to the 45 blank form shown in Fig. 5, having legs 16, bent downward to pass through two slots 17, in the top plate, and flanges 18, projecting at the sides, inserts its feet 18, under the shoulder 12, and between that and the ring 50 9, to lock the button to the stud and thereby to hold it attached to the garment. The

legs 16, after entering the top plate, are brought near enough together at their lower ends or feet 18, to engage the neck and shoulder of the stud, and the crossbar 20, 60 being broader than the remaining space between the feet, prevents the key from being separated from the head when not in service. While the key may fit so loosely under the shoulder that the button head will rotate 65 freely around it, yet any pull on the button brings the key to a rigid bearing and holds the parts firmly together. I provide each key with a hip 21, to spring outward and project a very little close under the top 70 plate to prevent the key from being worked out of place when in service, and yet this hip is not wide enough to prevent readily withdrawing the key by a person's finger nails. In order to form this hip at the right height 75 on the leg after being inserted in the head, I cut nicks 22, to weaken the leg at that point, and I press the legs upward on an outward slant to form the hips and also to give them a trough-shape to fit around the 80 stud neck and shoulder. In my earlier button referred to, the flanges 19, were provided to be engaged by a person's finger nails to withdraw the key enough to unlock the stud, but it was possible for those 85 sharp flanges to injure the quick under the nails, therefore I have provided the key with a cap 24, having smoothly turned under edges that cover and engage these flanges and extend in a circle around over the key 90 hips, and this cap may be safely grasped at any side or sides to remove the key. But it is found that the main advantage in extending the cap 24 out over the hips 21, is that it enables the operator to seize the key 95 at those sides and thereby to rock it to and fro in the plane of the legs while pulling to extract it. This creeping action first raising one leg and then the other enables the key to be withdrawn more easily 100 than can be done by seizing the cap at the flange—19—sides.

The modification represented at Fig. 6, shows at 25, the hips projecting inward to engage the crossbar 20, of the top plate. 105

What I believe to be new and desire to secure by Letters Patent is briefly stated in the following claims:

1. In a button, a stud having a broad base, a narrow neck, a shoulder above and 110 larger than the neck, and pointed at the top; a head comprising a top plate having two

- 2 slots in it and a crossbar between; a bottom plate and a ring with an opening through it to admit the said shoulder of the stud; a key having legs fitted to enter the said slots 5 in the head and to extend their feet between the stud shoulder and the surrounding ring; the legs having hips projecting close under the top plate.
2. In a button, a head; a stud adapted to 10 enter the bottom and a key adapted to enter the top thereof; the entering portion of the key being two legs with feet to engage the stud and hips to engage the top of the head;
- flanges projecting beyond the side lines of the legs at the top of the key; and a cap 15 having smoothly turned-under edges engaging the said flanges and extending freely over the said hips, whereby the key may be seized at points over the two legs for removal.
- 20 In testimony whereof I affix my signature in presence of two witnesses.

JOHN V. PILCHER.
